UNITED STATES PATENT OFFICE.

LEWIS B. ELA, OF WOLLASTON, MASSACHUSETTS.

GAME APPARATUS.

1,147,931.

Specification of Letters Patent. Patented July 27, 1915.

Application filed September 9, 1912, Serial No. 719,331. Renewed December 19, 1914. Serial No. 878,168.

To all whom it may concern:

Be it known that I, LEWIS B. ELA, a citizen of the United States, residing at Wollaston, county of Norfolk, Commonwealth 5 of Massachusetts, have invented certain new and useful Improvements in Game Apparatus, of which the following is a specification.

This invention relates to game apparatus 10 and particularly to an apparatus for playing a game involving the principles and elements of foot ball.

In the approximation of any sport involving physical exercise by a play apparatus 15 one great difficulty involved is that of reproducing in the conditions of the play a fair amount of the spirit of the game itself. This success depends on subtle elements. One of the features of the game of foot ball 20 which has made it most popular is the maneuvering of the teams on the field and the generalship exercised in directing the successive plays which position the teams in the contested territory.

25 In developing my conception of the game of foot ball, as reproduced with play apparatus, I have provided means and manner of play which give both the setting and movement of the game and also permit the discretion of the player to figure in the handling of the situations in which he finds himself during the play. I have accomplished this in brief by providing apparatus in which the field conditions are faithfully 30 reproduced and by which the exact movement and positioning of the "ball" may be obtained. By using a plurality of indicating devices, I permit selection of either method of advancing the ball, *i. e.*, by running or by kicking. Furthermore, I so provide the direction devices that they faithfully indicate gains, losses, penalties and the like with reference to the law of chance under actual conditions so that a chance indication becomes on the average a faithful 35 reproduction of the actual.

The construction of and practice with my apparatus will be more fully described in the specification which follows.

40 In the drawings I have shown the apparatus in an approved form.

Throughout specification and drawings like reference numerals are employed to indicate corresponding parts, and in the drawings: Figure 1 is a plan view of my folding board spread out open. Fig. 2 is a side view

of my movable marker shaped as a foot ball, and Fig. 3 is a section on the line 3—3, Fig. 2.

The apparatus which constitutes the preferred form of my invention comprises a board formed in two parts, 1 and 2, and hinged together at 3, so that the parts may be folded over each other. On the board 2 is the field 4 which is formed as an oblong 60 grid corresponding to the actual field, with a central line M indicating the middle of the field, and a goal line G at each end. The field is laterally subdivided by nine equally spaced lines on each side between the middle 65 line M and the goal lines G. These lines are numbered on each side "5" to "45", inclusive, by "5"s and correspond to what are known as the "5 yard" lines of the actual foot ball field. The field is transversely 70 divided by smaller lines ruled transversely of the "5 yard" lines which divide the field into vertical columns numbered from "1" to "20", inclusive. These vertical rulings are divided by transverse marks into five 75 subdivisions indicating the yards of each of the "5 yard" subdivisions.

The "ball" is a small piece, preferably of metal, shown in Figs. 2 and 3, comprising an oval shaped top 9 approximating a foot ball 80 in general outline, mounted on a base 9², having transverse pointers 9¹, which enable the "ball" to be positioned accurately with regard to the "1 yard" marks.

On the part 1 I form two indicators, 5 90 and 6, having pointers 7 and 8, which may be whirled on their pivots to give a chance indication upon coming to rest. The indicator 5 comprises a circular diagram of twenty-two subdivisions, each of substantially 95 sector shape. These subdivisions give in general the ordinary play by which the ball is carried, each subdivision being proportioned in accordance with the ordinary law of chance as actually occurring in the 100 game. That is to say the chance that the pointer will stop on any space is substantially the same in any given number of plays as is the chance of that play occurring in the actual playing of the real game of foot 105 ball.

At substantially opposite positions are two segments labeled "Run circle", one being followed by the indication letter A, the other by the indication letter B. These 110 "Run circles" A and B mean that the ball is carried in the play indicated for a con-

siderable distance, that distance being determined on either of two sets of indications A and B, on the indicator 6, which will be later described.

5 Following the run circle B, occurring on the right of the diagram 5, the next segment below is marked "Fumble". When the pointer 7 stops on this sector the play is supposed to have failed because of the fumble of the "ball".

10 The next lower sector is marked "8 yards". When the indicator point 7 stops on this sector, the ball is supposed to be advanced eight yards by ordinary ground gaining.

15 The next sector is marked "Block kick, lose 10 yards, hold ball", meaning that a kick has been blocked and the ball recovered ten yards behind the line.

20 The next sector is marked "10 yards" the play being supposed to be similar to that of the sector marked eight yards, but with an increased gain.

25 The next sector is marked "Lose 5 yards". When the pointer 7 falls on this sector the ball is carried back five yards from the point where it was supposed to be put in play.

30 The next sector is marked "Forward pass, circle A". This means that the play is a forward pass the length of which is determined by reference to the areas A, which will be later described in connection with the indicator 6.

35 The next play is "4 yards", meaning an advance of four yards by ordinary play as heretofore explained.

40 The next sector is another "Blocked kick", with an indicated loss of ten yards similar to that before described, but with a loss of the ball.

45 The next two sectors are "5 yards" and "9 yards" respectively, indicating the gain by ordinary advance of the ball.

50 The next sector is a "Fumble" corresponding to that heretofore described. This brings us again to the "Run circle A", as has been heretofore mentioned, which is followed by a sector of "3 yards", again followed by one of "15 yards loss". Then follow five sectors indicating gains of respectively "20 yards", "2 yards", "5 yards", "15 yards" and "3 yards".

55 The next sector indicates a "Fumble" with a "loss of 10 yards", but with a retention of the ball, and the next sector indicates an ordinary gain of "1 yard".

60 Outside of these sector indications are two bands, extending halfway around them, the longer one marked "Run back circle A"; the shorter, "Run back circle B". These refer to the circles A and B of the indicator 6. Opposite to these bands is an area of substantially one-half the circumference marked "Goal" and when the pointer lands within

its bounding radii, a goal is supposed to have been kicked.

65 The indicator 6 is employed to give the distance covered by all kicks, as well as for long runs and forward passes. The indicator 6 comprises a circular chart divided into three concentric bands, A, B, and C. These bands are divided by six radial lines *a*, which extend from the center outward to the periphery. The inner circle A is further divided by shorter radii *b*, bisecting the arcs of the sectors formed by the radii *a*. On one side of each of the subdivisions formed by the radii *b* is the word "Lose". This indicates that the distance indicated is a loss when the pointer falls on the "lose" side of the radii *b*. If it falls on the opposite side the amount indicated is gained. These sectors are denominated "10", "15", "20", "25", "30", and "35" yards. They represent the 70 various distances covered by the shorter kicks, and by forward passes, as well as by the shorter end runs or possible runs through the line where a large hole has been 75 opened.

80 The segments B composing the band line next outside of that just described, are denominated in the longer distances "30 yards", "55 yards", "35 yards", "45 yards", "40 yards", and "50 yards". In 85 the "30 yard", the "35 yard" and the "40 yard" segments, a radial subdivision is also made which is marked "Fumble". This introduces into these greater distances an element of uncertainty corresponding with the 90 chances of the game as they actually exist.

95 Outside of the sectors B is the band C which is divided into twenty-four sections, numbered from "1" to "20", with the numbers "12" to "15" inclusive also repeated 100 to complete the subdivision. These indications in the band C refer to the lateral placing of the "ball" on the field 4.

105 The game is played according to the general plan as outlined in the official foot ball rules as recognized in the United States. It will be understood that as these rules are subject to change from year to year, the provisions of my apparatus may require, both as regards my indicator and as regards the 110 details of the field, some corresponding changes.

115 In starting the game the players place themselves on opposite sides of the board, each behind his own goal line G. The party winning the toss places his "ball" over the spot K or K¹ whichever may be nearer to his goal line. As the ball is kicked off, the player having the kick off will spin the pointer 8 of the indicator 6. As soon as the indicator comes to a standstill the indication may be read. In the position shown in the drawings the indicator points to a kick of forty yards, landing in column 3. Supposing that the "ball" was kicked from 120 125 130

K¹ eight spaces would be counted off and the ball advanced to the "20 yard" line of the opponent in the column marked "3". The ball is therefore in the hands of the opponents and the next question to be determined after a kick is whether or not the player who has caught the ball has succeeded in "running the ball back" from the position in which he caught it. The "run back" band is on the indicator 5 and the

10 opponent therefore spins the pointer to see whether the player has been able to "run back" the ball. If the pointer falls in either of the "run back" bands A or B, the pointer 15 of the indicator 6 is spun to see how far he has been able to run it back.

It will be noted that the "run back" band A of the indicator 5 is much larger than the "run back" band referring to the circle B. 20 This is because the "run back" circle A is for short distances, while the "run back" circle B is for long distances, the chances being of course that the player who catches the ball will be unable to run back with it 25 very far.

Referring again to the drawings as they stand, it will be seen that the pointer 7, which we will suppose was spun by the opponent for a "run back," failed. It will 30 therefore be presumed that the player was "downed" in his tracks without either gain or loss. The opponents now having the "ball" have an option of trying for any one of the various plays provided for in the indicator 5, the greater part of which assures the possession of the ball from the spinning of the pointer 8 of the indicator 6. After a kick the ball goes into the possession of the other side. According to the usual policy 35 of the game the indicator therefore would be spun in the hope of carrying the ball back down the field by steady gains. The party therefore having possession of the ball would spin the pointer 7. We will suppose 40 that the pointer lands on the "1 yard" segments. The ball is therefore moved from the "20 yard" line to the indicated "21 yards" point.

It will be understood that according to 50 the present rules the ball must be advanced for a gain of ten yards in four "downs." If a distance of ten yards is not covered in the four tries the ball is forfeited. Under the supposed conditions noted, the player 55 will have had one try and will only have gone one yard of the ten which he has supposed to have gone. As he has three more "downs" he will probably spin the pointer 7 again. We will suppose for example that on this attempt the pointer 7 falls on the "15 yard" sector. The ball is then advanced to the "36 yard" point and the play becomes the first down as the required ten yards have been made.

We will suppose that on the next play the

pointer 7 shall fall on the sector which is indicated in the drawings and labeled "Fumble, lost 10 yards, hold ball." In accordance with this play the ball would be carried back ten yards to the "26 yard" point as it is supposed to have been dropped and recovered at that point. This leaves the opponent in possession of the ball and as ten yards have been lost he now has twenty yards to gain in three more downs.

75

We will suppose that on the next two plays the pointer 7 falls at "2 yards" and "5 yards" respectively. As this only makes a total advance of seven yards, according to the usual policy the player would then try 80 for a kick. For this purpose the pointer 8 of the indicator 6 would be spun. For the purpose of voluntary kicks the segments B are employed without regard to the winning or losing side of the radii B. A voluntary 85 kick is therefore certain to gain somewhere from thirty to fifty-five yards, provided that the pointer does not fall on one of the three "fumble" spaces. This offers the advantage which kicking actually offers in the game, 90 but like the real game places the ball in possession of the opposing team. In this way, the game is carried through, the ball being moved in one direction or the other toward the goal line G, and being placed laterally 95 in the columns "1" to "20," inclusive, whenever a long run or a kick is made.

The score is counted in the usual manner for touch downs, after which the side making the touch downs spins the pointer 7 to 100 see whether or not a goal is kicked.

The play works out in exact counterpart of the actual game, and the time of the game may be set in accordance with the desires of the player.

105

Various modifications may obviously be made in the details of the divisions or in the form and arrangement of the field, all without departing from the spirit of my invention if within the limits of the appended 110 claims.

What I therefore claim and desire to secure by Letters Patent is:

1. A foot ball game apparatus comprising a sectioned field, a movable marker, and two 115 independent chance devices, one having suitable indicia providing for the advance of the ball by kicking with a preponderance of indicated chance of losing possession of the ball, and the other having indicia primarily relating to the advance of the ball by other means and having a preponderance of indicated chance of retaining the possession of the ball.

2. A foot ball game apparatus comprising a sectioned field, a movable marker, and two independent chance devices, one having as an element an indication of the beginning of a play involving a considerable duration of time as a forward pass or the like, and 125 130

- the other an indication of the ultimate failure or success of said play and referred to by said first named device and also indicating the extent of said play.
- 5 3. A foot ball game apparatus comprising a sectioned field, a movable marker, and two independent chance devices, one of said chance devices having indicated plays of the following natures, a plurality of indicated plays showing the carrying of the ball by rushing for different distances, indicated possibilities of the loss of the ball, indicated possibilities of the carrying of the ball for an unindicated distance with reference to
- 10 15 the second chance device, indicated possibilities of kicking the ball for an unindicated distance with reference to said second chance device, indicated possibilities of advancing the ball by forward pass for an unindicated distance with reference to said second chance device, indicated losses; said second chance device containing the indications for distance for voluntary kicks, indicated loss of the ball by fumble or otherwise having a minimum chance relation to said distance indications, indicated distances for forward passes each having a substantially equal indication of chance of failure or success.
- 15 20 25 30 35 40 45 4. A foot ball game apparatus having possibilities for arbitrary play selection according to the individual judgment of the player comprising a sectioned play field, a movable marker, and two independent chance devices referable one to the other, one of said devices characterized by two independent play determining areas each bearing suitable indicia, one of said areas primarily providing for indicated long distance advancement of the ball by kicking with a preponderance of chances of losing possession of the ball but with indicated ball recovery designations having a minimum chance relation to said distance advancements, the other of said areas primarily providing for indicated short distance advancement of the ball by kicking or forward passing with substantially equal chances of failure or success and with minimum possibility of losing possession of the ball, and the other of said chance devices characterized by areas referable respectively to the play determining areas of the first described device and by areas with indicated possibilities of advancing the ball by tactics other than kicking with gain or loss and distances suitably proportioned according to the chances in the actual game.

chances of failure or success, and the other of said chance devices characterized by areas referable respectively to the play determining areas of the first described device and by areas with indicated possibilities of advancing the ball by tactics other than kicking with gain or loss and distances suitably proportioned according to the chances in the actual game.

5 10 15 20 25 30 35 40 45 50 55 60 65 70 75 80 85 90 95 5. A foot ball game apparatus having possibilities for arbitrary play selection according to the individual judgment of the player comprising a sectioned play field, a movable marker, and two independent chance devices referable one to the other, one of said devices characterized by two independent play determining areas each bearing suitable indicia, one of said areas primarily providing for indicated long distance advancement of the ball by kicking with a preponderance of chances of losing possession of the ball but with indicated ball recovery designations having a minimum chance relation to said distance advancements, the other of said areas primarily providing for indicated short distance advancement of the ball by kicking or forward passing with substantially equal chances of failure or success and with minimum possibility of losing possession of the ball, and the other of said chance devices characterized by areas referable respectively to the play determining areas of the first described device and by areas with indicated possibilities of advancing the ball by tactics other than kicking with gain or loss and distances suitably proportioned according to the chances in the actual game.

In testimony whereof I affix my signature in presence of two witnesses.
